INTERNAL-COMBUSTION ENGINE COOLING
SYSTEM

Thomas J. Bay, United States Navy

Application April 6, 1943, Serial No. 481,983

8 Claims. (Cl. 123—174)

(Granted under the act of March 3, 1883, as
amended April 30, 1928; 370 O. G. 757)

This invention relates to cooling systems for internal combustion engines and it has for its principal object the provision of an improved system for controlling the temperature of the lubricating oil thereof, and also for controlling the temperature of the engine cooling water.

The use of heat exchangers in connection with marine installations of internal combustion engines has become practically universal. A common arrangement for Diesel engine cooling systems provides two heat exchangers; one for cooling the engine jacket water and the other for cooling the engine lubricating oil. Sea water is circulated through these heat exchangers as the coolant; the usual arrangement providing for series flow of the sea water, first through lubricating oil heat exchanger and thence through the jacket water cooler.

A somewhat less common engine cooling system provides for cooling the engine jacket water, as described above, but instead of circulating sea water through the lubricating oil cooler the cooled jacket water is employed as the cooling medium. This type of cooling system has the advantage of exposing only one of the two heat exchangers or coolers to the corrosive action of sea water and the further advantage that, upon starting a cold engine, the engine and the lubricating oil and jacket water temperatures are elevated to the proper operating range much more rapidly than when the colder sea water is circulated through the lubricating oil cooler. This type of cooling system has the disadvantage of requiring the use of somewhat larger heat exchangers for a given installation which to some extent offsets the advantages derived therefrom.

However, the advantage obtained by circulating jacket water through the lubricating oil cooler, that is to say the initial rapid heating of the engine lubricating oil and maintenance of optimum lubricating oil temperature during operation, has become extremely important in view of current operations of Diesel engine propelled naval vessels in the Iceland-North Sea area and in the vicinity of the Aleutians. Reports received from vessels operating in these areas and not equipped for jacket water circulation through the lubricating oil coolers indicate that in many cases the chilled engine lubricating oil never reaches the proper operating temperature even after hours of engine operation, resulting in accelerated wear of all bearing surfaces, early engine failure, decreased reliability and excessive maintenance and repair requirements. This is

particularly true in the case of high speed Diesel engines and it has been definitely established that engine deterioration is very rapid whenever operation proceeds with either lubricating oil or jacket water circulating at a temperature below 130° F.

The principal object of the present invention is to avoid the difficulties encountered by the use of sea water circulation through the lubricating oil cooler and take maximum advantage of circulating jacket water through such cooler for rapid heating of the chilled lubricating oil upon starting cold engines and, in addition, providing for automatic control of the temperatures of the lubricating oil and jacket water within the optimum operating range, as specified by the engine designer, regardless of variations in the power at which the engine is operated or variations in the temperature of the sea water.

20 With these and other objects in view as well as other advantages that may be incident to the use of the improvements, the invention consists in the parts and combination thereof hereinafter set forth and claimed, with the understanding that the several necessary elements constituting the same may be varied in proportion and arrangement without departing from the nature and scope of the invention, as defined in the appended claims.

25 30 In order to make the invention more clearly understood, there are shown in the accompanying drawing means for carrying the invention into practical use, without limiting the improvements in their useful application to the particular construction, which, for the purpose of explanation, have been made the subject of illustration.

The single figure of the accompanying drawing is a diagrammatic view of a system of automatically controlling the temperature of the lubricating oil and jacket water of an internal combustion engine wherein the jacket water is employed to control the temperature of the lubricating oil.

40 45 Referring to the drawing, a system for controlling the temperature of the lubricating oil and jacket water of an internal combustion engine is shown as comprising generally an engine 10, a jacket water cooler 11 and a lubricating oil cooler 12. The jacket water cooler 11 is provided with a heat transfer element 13 through which sea water is circulated from a pipe 14 and valve 15 and from which the sea water escapes through a pipe 16. This cooler is also shown as 50 55 being provided with a heat transfer element 17

through which jacket water to be cooled is supplied from the engine through a pipe 18 and a three-way thermostatically controlled valve 19. The cooled jacket water escapes from the heat transfer element 17 through a pipe 20 which delivers this cooled water to a heat transfer element 21 of the lubricating oil heat exchanger 12 from which it flows back to the cooling water jacket of the engine 10 through a pipe 22. The lubricating oil heat exchanger contains a heat transfer element 23 through which lubricating oil from the engine 10 is delivered from a pipe 24 and from which it is delivered back to the engine through a pipe 25.

Jacket water from the engine 10 is at times by-passed around the jacket water cooler 11 through a by-pass pipe 26 and the three way valve 19, the control element 27 of which is placed in thermal contact with the jacket water leaving the engine, as indicated at 28. The utility and operation and function of this by-pass will be hereinafter explained. The sole purpose of the flow control valve 15 is to protect the jacket water cooler from excess flow of sea water and the same purpose can be served through the provision of a circulating water by-pass around this cooler.

Lubricating oil from the engine may also be by-passed around the lubricating oil heat exchanger and directly back to the engine through a by-pass pipe 29 and an automatic spring loaded pressure relief valve 30 when the engine is initially started. The by-pass pipe 29 can be arranged to by-pass other parts of the engine lubricating oil system as well as the heat exchanger 12, such as lubricating oil filters, strainers, etc. Thermometers 31 and pressure gauges 32 may be provided wherever desired.

In operation of this newly devised system the three-way temperature control valve 19 is first adjusted to by-pass the cold jacket water cooler 11 when the engine is initially started. With the engine in operation, the jacket water is heated very rapidly because this water is by-passing the jacket water cooler. This heated jacket water passing through the lubricating oil cooler provides for rapid heating of the chilled lubricating oil circulating through the oil heat exchanger.

In this connection, it will be understood that in most types of internal combustion engines the amount of heat dissipated into the jacket water by the operation of the engine is about ten times the amount of heat dissipated into the lubricating oil and, therefore, the jacket water is heating very much more rapidly than the lubricating oil upon starting a cold engine provided that the jacket water is constrained to by-pass the jacket water cooler. As the jacket water temperature becomes elevated to the operating range, the control element of the three-way temperature control valve in thermal contact with the heated jacket water tends to throttle the flow of jacket water through the by-pass and force sufficient jacket water through the jacket water cooler to maintain a constant predetermined temperature of the jacket water leaving the engine, regardless of the temperature of the sea water circulated through the jacket water cooler and regardless of variations in the power being generated by the engine.

With a constant temperature maintained in the jacket water leaving the engine through the operation of the temperature control valve, it will be noted that, at any given engine power,

the temperature of the jacket water and lubricating oil circulated to and from the engine remains absolutely constant regardless of all changes in the temperature or quantity of the sea water circulated through the jacket water cooler. This is readily apparent by reference to the drawing. At constant engine power, heat dissipated to and from the oil and jacket water in the engine and the heat exchangers or coolers is constant, therefore, with a constant engine jacket water discharge temperature, the temperature of the jacket water entering the engine is constant because the rise in temperature of the water flowing through the engine is constant. Thus, the temperature of the jacket water leaving the lubricating oil heat exchanger or cooler is constant and as the amount of heat dissipated to the jacket water from the lubricating oil in the lubricating oil heat exchanger is constant, the temperature rise of the jacket water and lubricating oil to and from the lubricating oil heat exchanger remains constant. Thus, regardless of changes in the temperature and quantity of the sea water, at any given engine power the oil and jacket water temperatures to and from the engine are maintained absolutely constant which is a very desirable engine operating condition from the standpoint of engine service life and reliability.

In certain installations and under certain conditions it may be found to be desirable to provide a jacket water by-pass pipe 33 having a fixed restricted orifice 34 therein and establishing communication directly from the jacket water discharge pipe 18 and the jacket water inlet pipe 22. The flow of water through this by-pass is automatically controlled by the fixed orifice 34, although in some cases it might be desirable to substitute a manually controlled valve in lieu of the fixed orifice 34. This modified system has all of the advantages as the system hereinbefore described as to the rapid heating of chilled lubricating oil on starting and automatic control of lubricating oil and jacket water temperatures. An additional advantage associated with this modified system applies to engine installations where it is desired to provide for a relatively small rise in temperature of the jacket water flowing through the engine and also to reduce the size of the lubricating oil heat exchanger to the minimum at the expense of a slight increase in the size of the jacket water cooler.

By means of the fixed by-pass arrangement, a predetermined quantity of heated jacket water is automatically by-passed around both coolers. The remaining jacket water is cooled to a lower temperature than would be obtained if the entire quantity of jacket water were circulated through the jacket water cooler. Thus, relatively cold water is circulated through the lubricating oil heat exchanger and the size of this unit can therefore be reduced as compared to the size required if warmer water were circulated through this heat exchanger.

The uncooled jacket water flowing through the fixed orifice 34 in the by-pass pipe 33 mixes with the cooler jacket water discharging from the lubricating oil heat exchanger and the resulting mixture flowing to the engine is warmer than would normally be obtained if the full quantity of jacket water were passed through the two heat exchangers. By properly proportioning the size of the heat exchangers and that of the by-pass 33 and fixed orifice 34 it is possible to

provide for cooling the lubricating oil flowing to the engine to a temperature as low or even lower than the temperature of the jacket water flowing to the engine. Also, this arrangement renders possible a minimum temperature rise of the jacket water flowing through the engine, which is very desirable for certain types of engine installations.

From the foregoing it will be apparent that a very efficient system is provided for controlling the temperature of both the cooling water of the engine and the lubricating oil thereof by means of which the service life of internal combustion engines is materially extended, the reliability of the engines is improved and the necessity for maintenance and repair decreased. Also, the improved system insures the rapid heating of chilled lubricating oil upon starting a cold engine and the rapid warming up of a cold engine upon starting. The temperatures of the jacket water and lubricating oil is controlled entirely automatically. The lubricating oil heat exchanger is not subjected to the corrosive action of sea water. The improved system permits of a simplified piping arrangement with only one automatic control valve necessary for the regulation of the temperatures of both the jacket water and the lubricating oil. The system has the additional advantage of providing for relatively small temperature rise of jacket water circulated through the engine with minimum size of lubricating oil heat exchangers.

It will be understood that, whereas the above description of the present engine cooling system is particularly adaptable to marine engine installations it is equally applicable to all other internal combustion engine installations. For land installations the term "sea water" as employed herein may be more properly termed "raw water" or a "cooling fluid obtained from an external source" and for aircraft installations the primary cooling medium is air. It will also be understood that the control element 28 of the three-way temperature control valve 19 may be located at various other points in the jacket water circuit or in the lubricating oil circuit with generally similar results depending on proper design and adjustment of the automatic control feature. Also, the three-way temperature control valve 19 may be located at the opposite end of the jacket water cooler by-pass pipe 26 or at either end of a sea water by-pass pipe around the jacket water cooler or a manually controlled valve may be employed in lieu of an automatically controlled valve. It will be understood further that a two-way temperature control valve may be substituted for the three-way valve shown with similar results provided that the cooling system is proportioned so as to provide for relatively small pressure drop through the jacket water by-pass pipe 26 as compared to the pressure drop through the jacket water circuit of the jacket water cooler.

It will be understood, as previously stated, that the above description and accompanying drawing comprehend only the general and preferred embodiment of the invention and that various changes in construction, proportion and arrangement of the parts may be made within the scope of the appended claims without sacrificing any of the advantages of the invention.

The invention described herein may be manufactured and used by or for the Government of the United States of America for governmental

purposes without the payment of any royalties thereon or therefor.

What is claimed is:

1. A system for controlling the temperature of the cooling water and that of the lubricating oil for an internal combustion engine wherein a first heat exchanger cools the water flowing from the engine and a second heat exchanger through which lubricating oil from said engine is circulated, the heat transferring capability of which is controlled by the water flowing from said first heat exchanger, controls the temperature of said lubricating oil; characterized by the fact that there is combined with said first heat exchanger, means for by-passing the heated water flowing from the engine cooling system around said first heat exchanger for delivery directly to said second heat exchanger in a heated condition in order to elevate the temperature of said lubricating oil.
2. A system for controlling the temperature of the cooling water and that of the lubricating oil for an internal combustion engine wherein a first heat exchanger cools the water flowing from the engine and a second heat exchanger through which lubricating oil from said engine is circulated, the heat transferring capability of which is controlled by the water flowing from said first heat exchanger, controls the temperature of said lubricating oil; characterized by the fact that there is combined with said first heat exchanger, means for by-passing a portion of the heated water flowing from the engine cooling system around said first heat exchanger for delivery directly to said second heat exchanger in a heated condition to maintain the engine lubricating oil at the desired operating temperature.
3. A system for controlling the temperature of the cooling water and that of the lubricating oil for an internal combustion engine wherein a first heat exchanger cools the water flowing from the engine and a second heat exchanger through which lubricating oil from said engine is circulated, the heat transferring capability of which is controlled by the water flowing from said first heat exchanger, controls the temperature of said lubricating oil; characterized by the fact that there is combined with said first heat exchanger, means for by-passing a portion of the heated water flowing from the engine cooling system around said first heat exchanger for delivery directly to said second heat exchanger in a heated condition to maintain the engine cooling water and the engine lubricating oil at the desired operating temperature.
4. A system for controlling the temperature of the cooling water and that of the lubricating oil for an internal combustion engine wherein a first heat exchanger cools the water flowing from the engine and a second heat exchanger through which lubricating oil from said engine is circulated, the heat transferring capability of which is controlled by the water flowing from said first heat exchanger, controls the temperature of said lubricating oil; characterized by the fact that there is combined with said first heat exchanger means controlled by the temperature of the engine cooling water for by-passing the heated water flowing from the engine cooling system around said first heat exchanger for delivery directly to said second heat exchanger in a heated condition in order to maintain the en-

gine lubricating oil at the desired operating temperature.

5. A system for controlling the temperature of the cooling water and that of the lubricating oil for an internal combustion engine wherein a first heat exchanger cools the water flowing from the engine and a second heat exchanger through which lubricating oil from said engine is circulated, the heat transferring capability of which is controlled by the water flowing from said first heat exchanger, controls the temperature of said lubricating oil; characterized by the fact that there is combined with said first heat exchanger, a thermally controlled means for bypassing the heated water flowing from the engine cooling system around said first heat exchanger for delivery directly to said second heat exchanger in a heated condition to maintain the engine cooling water and the engine lubricating oil at the desired operating temperature.

6. A system for controlling the temperature of the cooling water and that of the lubricating oil for an internal combustion engine wherein a first heat exchanger cools the water flowing from the engine and a second heat exchanger, the heat transferring capability of which is controlled by the water flowing from said first heat exchanger, controls the temperature of said lubricating oil; characterized by the fact that there is combined with said first heat exchanger, means for bypassing the heated water flowing from the engine cooling system around said first heat exchanger for delivery directly to said second heat exchanger in order to elevate the temperature and lower the heat absorbing capability thereof, thus to maintain the engine lubricating oil at the desired operating temperature, and means for bypassing a portion of the heated water flowing from said engine cooling system around both of said heat exchangers for delivery directly back to said engine cooling system, to permit the temperature of said lubricating oil to be reduced if desired below the temperature of the engine cooling water entering the engine.

7. A system for controlling the temperature of the cooling water and that of the lubricating oil for an internal combustion engine wherein a first heat exchanger cools the water flowing from the engine and a second heat exchanger, the heat transferring capability of which is controlled by the water flowing from said first heat exchanger, controls the temperature of said lubricating oil; characterized by the fact that there is combined with said first heat exchanger, means for bypassing the heated water flowing from the engine cooling system around said first heat exchanger for delivery directly to said second heat exchanger in order to elevate the temperature and lower the heat absorbing capability thereof, thus to maintain the engine cooling water and the engine lubricating oil at the desired operating temperature, and means for bypassing a portion of the heated water flowing from said engine cooling system around both of said heat exchangers for delivery directly back to said engine cooling system, to permit the temperature of said lubricating oil to be reduced if desired below the temperature of the engine cooling water entering the engine.

8. A system for controlling the temperature of the cooling water and that of the lubricating oil for an internal combustion engine wherein a first heat exchanger cools the water flowing from the engine and a second heat exchanger, the heat transferring capability of which is controlled by the water flowing from said first heat exchanger, controls the temperature of said lubricating oil; characterized by the fact that there is provided means for bypassing a portion of the heated water flowing from said engine cooling system around both of said heat exchangers for delivery directly back to said engine cooling system, to permit the temperature of said lubricating oil to be reduced if desired below the temperature of the engine cooling water entering the engine.
